UNITED STATES PATENT OFFICE.

DAVID B. EDMONSTON, OF WASHINGTON, DISTRICT OF COLUMBIA.

GOLF-PRACTICING DEVICE.

Application filed November 6, 1924. Serial No. 748,139.

To all whom it may concern:

Be it known that I, DAVID B. EDMONSTON, a citizen of the United States, residing at Washington, in the District of Columbia, 5 have invented certain new and useful Improvements in Golf-Practicing Devices, of which the following is a specification.

This invention relates to devices for practicing golf indoors and particularly the 10 strokes known as putting, whereby facility and skill may be acquired in putting strokes, and the device may be used either individually or competitively by several persons.

One of the main objects of the invention 15 is to provide a device which may be used indoors and which will simulate as closely as possible the conditions found on putting greens. I am aware that devices have been proposed for practicing putting indoors. 20 Some of these involve an inclined plane up which the ball must roll to drop in the hole. Others use various forms of triggers or trapping devices. These are defective or objectionable because of the increased power 25 or drive required to move the ball up the plane or beyond the triggers; in other words, a stroke will not be true with respect to the power required. They are also open to objection on account of cost or otherwise.

30 A further object of the invention is to provide a device which may be applied to the edge of a rug or the like, the base of the device having substantially the same thickness as the rug, whereby the course or 35 surface on which the ball rolls will be substantially level, without elevations or obstructions to obstruct or deflect the travel of the ball.

A further object of the invention is to 40 provide an improved device of the kind stated in which the ball, having once entered the hole, will be retained therein, in a manner similar to a hole in the ground, except in the case of such hard stroke that the ball 45 would jump the hole under outdoor conditions, in which event the present device enables it to rebound out of the hole. This object is effected by the use of a retaining device which is so located and positioned 50 that the ball will be stopped or caught thereby and be held in the hole, so that it will not overrun the same or rebound out of the hole, except under the abnormal condition referred to.

55 A further object of the invention is to

provide a device which will deflect or retain the ball in the hole after marginal shots, that is, shots in which the ball travels to one of the lateral edges of the hole, with respect to its line of travel and with which, under ground conditions, the ball would drop into the hole, but with which, in the use of some of such indoor devices, the tendency is to deflect the ball away from the hole, or prevent it from dropping therein. 60 In short, the purpose of the device is to produce a result, with respect to the fall of the ball in the hole, the same as that found under outdoor conditions.

A further object of the invention is to 70 provide a device which will stop balls which miss the hole, and prevent the same from rolling around the room, under articles of furniture or the like.

A further object of the invention is to 75 provide means for retaining the device in position at the edge of a rug, mat or carpet to which it may be applied.

With these and other objects in view one 80 form of the invention is hereinafter described and is illustrated in the accompanying drawings in which Fig. 1 is a perspective view of the device. Fig. 2 is a sectional view on the line 2—2 of Fig. 1 illustrating a ball caught by the retainer. Fig. 3 is a 85 section on the line 3—3 of Fig. 2. Fig. 4 is a section on the line 4—4 of Fig. 1.

Referring particularly to the drawings, 90 6 indicates a rug, mat or carpet to the edge of which the device is applied. This device has a base board 7, of substantially the same thickness as the rug, whereby its top surface will be at substantially the same level as the surface of the rug. This board or base may be of any suitable material and desired dimensions. I have found between two and three feet a convenient length and about seven inches a convenient width. The material may conveniently be that known as compressed paper or wall board, a composition having qualities which are quite suitable for the intended purpose. The base has a circular hole 8 which may be made of standard size of holes in putting greens, said hole being preferably located at the 100 middle of the board. It may be set somewhat closer to the front edge of the board than is shown in the drawing. At its rear edge, the base has a back strip 9 fixed thereto, and at its ends has end strips 10. These 105 110

strips may be an inch or two high and may be made of wood, and they form a three-sided enclosure which will retain wild balls and prevent them rolling about the room.

5 To the back strip 9 is fixed a retainer or holding device indicated at 11. This may conveniently consist of a piece of composition board of little or no elasticity, being quite stiff or hard in fact, and it may be 10 fixed to the back strip by being set in a notch 12 in the top of the strip. The construction and location of this retainer is of considerable importance. It is set on the back strip at a slight inclination upwardly 15 and forwardly, as shown in Fig. 2, and its front edge projects somewhat over the hole 8, sufficiently far that a ball will engage said edge before it would engage the rear edge of the hole. Said front edge is curved, as 20 indicated at 13, on an arc concentric with that of the hole, whereby two horns or points 14 are formed. These horns or points are blunt, and the edge 13 is located in such vertical position that a standard 25 golf ball, as indicated at 15, will just enter or engage the said edge and will be pinched and held thereby when driven with sufficient force to strike the retainer. As stated, the material is "dead" or without elasticity sufficient to cause a rebounding action sufficient to cause the ball to leave the hole under a normal stroke, but when the stroke is abnormally hard, the elasticity of the ball 30 will cause it to rebound out of the hole. In 35 other words, if the stroke is such that under outdoor conditions the ball would drop in the hole, the retainer will act as stated, and remain in the hole, but if the stroke is so hard that under outdoor conditions the ball 40 would jump or travel over the hole, in such case the ball, instead of dropping into the hole to be engaged by the edge of the retainer will strike the said edge a sufficient 45 distance below the top of the ball to cause a rebounding action, which will throw the ball back out of the hole. Accordingly, the device has an action very nearly the same, with respect to the final result, as 50 that produced under outdoor conditions where, if the ball "hugs" the green, it will fall into the hole, but if hit sufficiently hard will travel clear over the hole, the intent of the present invention being to stop and hold the balls of the first kind, but permit 55 a rebound of the balls of the second kind. The horns 14 are blunted so that they will not become mashed in by repeated contact of a ball against the same. The edge 13 is curved so that it will accommodate balls 60 driven from various angles.

The horns 14 are also located in such position that they correspond to the vertical axis or the center line of a ball which may enter the rim of the cup at either side. 65 That is, assuming a ball traveling across the

70 rim of the hole at one side, if its vertical axial line is within the rim of the cup it will engage the horn and be deflected or retained in the hole, whereas if its vertical axis is outside a perpendicular dropped from the horn 14 it will "rim the hole" and be deflected outside. This corresponds to the action of a ball on the hole of a putting green, which will fall into the hole if its vertical axis is inside the rim but will rim the hole if outside. Under such conditions, with this device, the ball will be caught by the horn 14, and be retained in the hole, and thereby perfect the stroke.

75 As stated, the height of the curved edge of the retainer, and the slight inclination of the latter, are such as to just allow a ball to be pinched by the retainer, by reason of the curvature of its top surface, thus preventing it from leaving the hole under an 80 ordinary stroke.

85 With the use of the device, it will be found that if the ball is driven with just sufficient force it will drop into and stay in the hole. If slightly excessive force is used 90 a ball that hits the hole will engage the edge of the retainer and will be stopped and held in the hole. A retainer made of comparatively rigid inelastic material, such as composition, will be found superior to the use 95 of wood or the like for this purpose, but obviously the material may be varied as found suitable.

100 For holding the device in position at the edge of a rug or mat, I provide a pair of attaching devices shown as flexible metal strips 16 fastened to the edge of the board 7 adjacent the rug and provided at their free ends with pins 17. When the device is 105 applied to the edge of a rug the strips are placed under said edge and the rug pressed down upon the pins, being thereby hooked thereto and held in position against accidental displacement. And the surface of the 110 rug and that of the base 7 will be at substantially the same level so that the ball will not bounce or jump but will roll across the joint.

115 In using the device it is applied to the edge of a rug as stated. Then the ball is placed at a suitable or desired distance from the device and upon being hit by a putter will roll toward the hole. If it misses, it will be stopped and caught by the back and side strips. If it hits the hole, it will be held 120 therein to complete the stroke, except in cases of excessive force as above referred to. It may thus be used for individual practice or in competition players may play in succession, and keep a score as in the actual 125 game. Being constructed of inexpensive materials, the device can be cheaply manufactured and will give a near approach to the actual playing conditions of the regular outdoor game. The ball can be removed 130

from the device by a mere tap by the blade of the putter, so it is unnecessary to stoop and pick the ball out, as in some other devices, which becomes very tiresome on repetition. Also, several balls may be holed in succession, without removing the preceding balls. This saves time and travel back and forth.

The particular description of the form shown, and the materials used, is not to be regarded as a limitation thereto, but various changes or modifications may be made within the scope of the following claims.

I claim:

1. In a device of the kind described, a base board having a hole therein, and a fixed retainer projecting over the hole at a proper height to frictionally engage the top of a ball entering the hole.

2. In a device of the kind described, a base board having a hole therein, and a rigid retainer projecting above the board in position to engage a ball in the hole, the front edge of the retainer having the form of a forwardly presented concave curve.

3. A device as set forth in claim 2, said curve being concentric to the curvature of the rim of the hole.

4. A device as set forth in claim 2, the points at the ends of said curved edge being located within the vertical plane of the rim of the hole.

5. A device as set forth in claim 2, the points at the ends of said curved edge each being in position substantially in line with

the vertical axis of a ball entering the extreme side edge of the hole.

6. A device of the kind described, comprising a base board having a hole therein and adapted to be applied to the edge of a rug or the like, the thickness of the board being substantially equal to that of the rug, and means to fasten the edge of the board to the edge of the rug.

7. A device as set forth in claim 6, said board being provided with a back stop strip at the rear edge thereof.

8. A device as set forth in claim 6, the rear and side edges of the board having stop strips for the purpose described.

9. In a device of the kind described, a base board having a hole therein, a back strip at the rear edge of the board, and a retainer projecting forwardly from said back strip with its front edge over the hole at a proper height to engage a ball thereby.

10. A device as set forth in claim 9, said retainer being inclined slightly upwardly and forwardly from the back strip.

11. A device as set forth in claim 9, said retainer being inclined upwardly and forwardly from the back strip and having a concave front edge located over the hole at a proper height to engage thereby a ball in the hole.

In testimony whereof, I affix my signature in presence of a witness.

DAVID B. EDMONSTON.
